UNITED STATES PATENT OFFICE.

PATRICK F. QUINN, OF CORONA, NEW YORK.

DRESS-FORM.

1,239,721.

Specification of Letters Patent. Patented Sept. 11, 1917.

Application filed October 31, 1912. Serial No. 728,862.

To all whom it may concern:

Be it known that I, PATRICK F. QUINN, a citizen of the United States, residing at Corona, county of Queens, and State of New York, have invented certain new and useful Improvements in Dress-Forms, fully described and represented in the following specification and the accompanying drawings, forming a part of the same.

10 This invention relates to that class of apparel apparatus known in the art as dress forms, and the invention resides in a dress form of novel character and construction.

It is an especial object of the invention to 15 provide a dress form so constructed that it may, when not in use, be packed or stored in a very much smaller space than the forms now in use, either those of the adjustable or non-adjustable type; a dress form which 20 in weight will be very much less than the types of forms now in use; a dress form which can be cheaply made, but which, at the same time, will be durable and capable of performing the uses to which it may be 25 put.

Broadly considered, the dress form of the present invention comprises a plurality of sections or leaves of suitable material so connected together that they may be folded one 30 upon the other when the form is not in use, but which may be quickly unfolded and positioned to produce the form. These sections are pivotally connected and are arranged when unfolded to extend radially 35 from a common center, the outer edges of the sections being variously shaped, so that when the sections are unfolded or opened and brought into position, a form of the desired shape will be produced.

40 A detailed description of the invention, embodied in what is considered the best construction for carrying it into effect, will give a better understanding thereof, and such description will now be given in connection 45 with the accompanying drawings, in which—

Figure 1 is a front elevation of a form, the form shown being what is known as a bust form, and shown in its unfolded or open position;

50 Fig. 2 is a top view, partly in section, of the form shown in Fig. 1;

Fig. 3 is a perspective view of the form folded together and removed from a supporting standard;

55 Fig. 4 is a view partly in cross section

showing the connecting devices for securing the sections together;

Fig. 5 is a view of one of the connecting hinges;

Fig. 6 is a view, partly in section and partly broken away, of the preferred means for holding the form rigidly in open position;

Fig. 7 is a detail view showing one of the preferred forms of the spacing devices employed for limiting the opening movement of the sections, and

Fig. 8 is a detail view, partly broken away, of a convenient device for increasing the length of the form.

Referring now to these drawings, the form shown is what is known as a bust form which includes the configuration of a bust and the upper portion of the hips. The form in accordance with the invention is composed of a plurality of sections 1 which are secured together so that they may be folded upon each other lengthwise. The sections 1 are preferably flat or leaf-shaped and composed of suitable light material, such as papier mâché. The outline of the outer edge of each section is such that when the sections are assembled and opened out or unfolded, as shown in Fig. 1, a form of the desired dimensions and configuration is produced, each of the sections or leaves being for this purpose of somewhat different shape along its outer edge. The inner edges of the sections are straight and when the form is opened are adapted to come close together and extend radially from a common center, as clearly shown in Fig. 2. The sections are connected or secured together so that they may be folded on one another lengthwise, as shown in Fig. 3, and thus be capable, when the form is not in use, of being packed into an exceedingly small space. The construction employed for so connecting the sections may be somewhat varied, but preferably the sections will be connected together pivotally so that they may be 90

readily folded and unfolded. In the construction illustrated, each of the sections is provided with a hinge 2 of metal or other suitable material secured thereto as by rivets. The hinge 2 is formed as by slitting and bending, with oppositely disposed ears 4, one of

which is in a plane above the other, as shown in Fig. 5. These ears receive pivot pins 5. With this construction in uniting the sections, each section is connected with the succeeding section, the lower ear of one of the hinges 2 being positioned under the upper ear of an adjacent hinge, the pivot pin passing through the two superposed ears. This means of connecting the sections is an exceedingly convenient one in that such connections require little space, and when folded together, as shown in Fig. 3, the leaves or sections fold together compactly.

Means are preferably provided whereby the movement of the sections when unfolded to the position shown in Fig. 1 is limited so that the sections will be retained in their proper relative position and produce the desired configuration for the form. These means may be varied, but preferably will operate on the outer edges of the sections. Furthermore, they will be of such character as to be yielding and not interfere with the folding up of the sections into the desired small compass, and, furthermore, will be of such character that each two adjacent sections will be connected so that they will assist in opening the form and provide a construction whereby the sections of the form may be simultaneously unfolded or brought into open position. In Fig. 1 such a means is shown, consisting of tapes 6, 7, 8 and 9, secured to the edges of each of the sections as by stitching, these tapes extending circumferentially around the form and preferably being four in number located at the waist, bust, lower edge of the form and at the neck. If desired, shoulder straps 11 may be provided passing over and connecting the sections where they form the shoulder portions of the form, on the upper edges of such sections, the strips if desired consisting of tapes and acting to more firmly hold the sections in desired position. If desired, however, instead of the tapes sewed to the outer edges of the sections, strips or tapes 12 may be employed which are secured to the sections by rivets 13, and clips 14, as illustrated in Fig. 7, this construction being somewhat stronger and more durable than that shown in Fig. 1.

When the form is opened, as shown in Fig. 1, it is desirable that fastening means be provided for securing the last two sections rigidly in place, so as to hold the form in position while it is being used. Various devices may be employed for that purpose, such as the hook and eye, 15, as illustrated in Figs. 1 and 4, these hooks and eyes being attached respectively to the end sections 16 and 17. A better construction for this purpose, however, is illustrated in Fig. 6, in which there is provided a clip 18 pivotally secured at 19 to one of the end sections as 16 of the form, this clip being

of dimensions to embrace the two meeting edges of the last two sections 16, 17 of the form, and hold the same firmly in position.

The form may be, if desired, used without any additional support, the user simply standing it on a bench, table or other convenient and suitable place. In some instances it is desirable that a support or stand be provided, and such a stand of improved construction is provided by the invention, though, if desired, other stands may be employed.

As illustrated, the support provided by the present invention includes a foot 20 of improved construction which is formed of sections 21 foldable about a supporting rod 22. These sections 21 may be made of heavy leaves or sheets of papier mâché or card board, or other suitable material, and secured when in unfolded position by suitable fastening devices, as, for instance, a clip like the clip 18 which may be pivotally secured to one of the end sections of the foot. The sections 21 are hinged together by hinges similar to those marked 4 above described, such hinges being provided at the top and bottom of each section. The rod 22 is formed with an enlarged portion 31 which lies between the sets of hinges and forms a support for the sections. This rod 22 telescopes into a rod 23 which supports the form adjustably through a collar and set screw 24 by which the form may be elevated or depressed, as desired. A suitable cap piece 26 may be provided if desired.

A suitable covering 27 of yielding material, indicated in dotted lines in Fig. 1, may be used to cover the form when desired. This covering may be removed when the form is to be folded up, if desired, or may be folded up with the form.

As before stated, the invention shown is applied to a bust form. It will be understood, however, that it can be applied to any length of form desirable. If a form with full hips is desired, a convenient attachment is provided by the present invention whereby the form may be lengthened to those dimensions, or to longer dimensions if desired. In the construction illustrated, each of the sections is provided at or near its outer edge with an extension member 28 which is in the form of a looped wire which passes through and is held by guide clips 29 which are riveted at 30 to the bottom of each of the sections. When it is desired to employ a form of somewhat longer dimensions than that illustrated in Fig. 1, the operator simply pulls the member 28 to the position shown in dotted lines in Fig. 8.

It will thus be seen that a novel type of dress form has been produced by the present invention and one which is exceedingly convenient because of the ease of manipu-

lation, saving of space required in packing or storing, and cheapness. Furthermore, because of these advantages, a user may have a large number of forms of different sizes and dimensions, which may be used in place of the cumbersome, heavy and expensive forms now in use.

The invention has been shown and described in its preferred form. It is obvious, however, that many changes and variations may be made in the same without departing from the invention, and it is understood that such changes and departures may be made without affecting the scope of the invention.

Copies of this patent may be obtained for five cents each, by addressing the "Commissioner of Patents
Washington, D. C."

What is claimed is:—

In a dress form, a plurality of connected sections foldable one on the other and having their outer edges contoured to a bust and hip shape, and a looped wire slidable in 20 guides on the lower end of each section for lengthening the sections.

In testimony whereof, I have hereunto set my hand, in the presence of two subscribing witnesses.

PATRICK F. QUINN.
